United States Patent Office.

SAMUEL BRISTOW, OF BEDFORD, INDIANA.

Letters Patent No. 60,855, dated January 1, 1867

IMPROVEMENT IN SAW-MILLS.

The Schedule referred to in these Letters Patent and making part of the same.

TO ALL WHOM IT MAY CONCERN:

Be it known that I, SAMUEL BRISTOW, of Bedford, in the county of Lawrence, and State of Indiana, have invented a new and improved Log Adjuster; and I do hereby declare that the following is a full, clear, and exact description thereof.

The object of my invention is to lessen the labor of those in attendance upon saw-mills, and the invention consists in arranging shafts, with drum and wheels on them, in such a manner that, with a lever and pulley and rope and chains, one man may be able to handle saw-logs with ease.

And to enable others skilled in the art to make and use my invention, I will proceed to describe its construction and operation, reference being had to the accompanying drawings, which form a part of this specification, and to the letters of reference marked thereon.

Figure 1 represents an end view; and

Figure 2, a plan or top view.

Similar letters indicate like parts.

A represents the shaft from which the machine is operated. B is a pulley which drives the shaft by a belt from the engine. C is a grooved pulley on the shaft A. D is another shaft lying parallel with the shaft A. E is another grooved pulley on the shaft D, and corresponding in position with the pulley C, so that a chain or rope will work on them both. The shaft D forms a drum, D', around which the draw-rope is wound. F is a lever, with which the chain, h, is tightened, which works on the pulleys. One end of the drum shaft D is movable by the lever F. The post or standard which supports the bearing or journal of this end of the shaft is so arranged that the chain can be loosened or tightened by the lever. When it is loose, the drum stops its motion; when it is tightened on the pulleys, the drum revolves with the driving shaft. G is a sheave, suspended from the arm, H, and over which the draw-rope runs. J is the draw-rope. It is attached to the drum D'. The other end extends out from the drum and over the pulley. A chain may be attached to the end of the rope, with a hook, k, at the end. A chain may be employed altogether instead of a rope. To turn a saw-log, pass the hook under the log, and fasten it to the side next the lever. Then tighten the chain, which causes the drum to be revolved, and the power of the engine will do the rest. For rolling logs to the carriage, pass the hook under the middle of the log, and fasten it to one of the timbers of the mill. Then tighten the chain as before, and the power which drives the mill will do the work.

By this improvement a great saving of labor is effected in tending saw-mills. I do not confine myself to the manner of construction as represented in the drawing. I merely wish to show the shafts and working parts, without much reference to their relative positions when in actual use.

Having thus described my invention, what I claim as new, and desire to secure by Letters Patent, is—

The grooved pulley E on the drum shaft D, one end of said shaft having bearings in a movable standard, grooved pulley C on the driving shaft A, chain h and lever F, when constructed and arranged as herein set forth.

The above specification of my invention signed by me this 24th day of September, 1866.

SAMUEL BRISTOW
